COMBINATION PESSARY AND VAGINAL SUPPOSITORY

George A. Cruickshank, Providence, R. I.

Application August 6, 1934, Serial No. 738,605

15 Claims. (Cl. 128—271)

My invention relates to improvements in combination pessaries and suppositories.

Objects of my invention are to provide a combination pessary and suppository useful in the prevention of venereal diseases, and useful in the treatment of other infections or disorders of the cervix, uterus and vagina. Pessaries are broadly speaking of two types, (1) a detachable cervical cap type constructed of material capable of repeated use, preferably rubber which compactly fits over the cervix as evidenced in French pessaries, mizpah pessaries, pro-race pessaries, metal cap pessaries, etc. and is retained thereon partly by friction, partly by suction and partly by the rim's purchase on the vaginal walls and (2) rubber diaphragm pessaries including those of the mensinga and ramses type, usually circumscribed by a resilient member, adapted to be inserted in the vagina and retained over the upper surface thereof by having the rear end of the resilient member thereof abut the rear surface of the posterior cul de sac and the front end abut the inner surface of the vagina behind the symphosis pubis thus substantially cutting off the upper portion of the vagina and the cervix from the lower portion of the vagina. Vaginal suppositories have consisted of material usually soluble at body temperature containing medicament and are usually inserted in the vagina to melt therein. These, however, have proved ineffectacious in many cases when used alone because (1) they do not always melt and their operation is therefore uncertain and (2) they do not protect the os cervix from direct introduction of infected semen.

Where pessaries such as the aforementioned diaphragms or cervical caps of rubber, metal, celluloid, etc. have been employed, they have required the additional use of medicated suppositories, jellies, effervescent tablets, etc. involving considerable aesthetic interference because the cap must be lubricated with soapy water, ointment or jelly before insertion and it must be washed, sterilized and dried after use. In addition, these former types of devices are relatively complicated, inconvenient and time consuming in attaching and detaching and too expensive for the poorer class of people who suffer most from the results of venereal infection.

An object of my invention, therefore, is to provide a combination pessary and suppository which is consumable in one period of use, capable of retaining its position for several hours, and designed to be thrown away after use.

A further object of my invention is to pro-

vide an effective combination pessary and suppository, which requires no preparation whatsoever, is self-lubricating, can be inserted in a few seconds, once in place requires no attention, it being substantially as each to detach as to attach, and thus providing a device which covers the opening of the cervix, which can be attached and detached in a few seconds and can be produced at such a relatively small cost as to be within the reach of all classes of people. 10

A further object of my invention is to provide a combination pessary and suppository preferably having inclined inner walls so as to fit over cervices of different sizes and be closely adherent thereupon in use by suction and friction. 15

A further object of my invention is to provide a device comprising an imperforate frame or body which completely covers the os cervix and positively cuts off any direct approach from the urethra of the infected male to the os cervix. 20

A further feature of my invention is to provide a pessary having a body constructed of a material slowly soluble at body temperature to insure the provision of a medicament to the parts involved over a relatively long period of time as 25 contra-distinguished from an effervescent tablet, douche, etc. whose period of effective disinfection is relatively short.

A further object of my invention is to provide my thus shaped combination pessary and suppository with an outer covering and an inner covering if desired, including a medicament, immediately soluble at body temperature, so that if inserted by the female there will be present a relatively large amount of germ killing disinfectant at the dangerous period. I preferably provide an outer covering to immediately release said supply of medicament in the vagina adjacent the male organ and an inner globule or covering for the inner surface of the head of the pessary 40 to immediately release a supply of medicament immediately adjacent the os cervix. With the body melting at slightly above and the outer layer and the inner globule melting at slightly below body temperature, an antiseptic, medicament incorporated in the body, outer layer and inner globule is brought into direct contact with the microorganisms which it is desired to destroy both immediately on insertion and for a 45 relatively long time thereafter. 50

A further object of my invention is to provide a combination pessary and suppository which may be constructed at a very small cost, of various sizes to fit different size cervices, made to order to fit abnormal cervices and in which 55

by doctors' prescription any desired type of medicament may be incorporated in both the inner and outer layers thereof.

Further objects of my invention are to incorporate the advantages of chemical methods with those of mechanical methods, without the attendant disadvantages of "aesthetic" interference at any time, trouble of caring for the pessary, expensive apparatus and difficulty of use.

10 A further object of my invention is to provide a pessary which as the outer surfaces thereof are immediately soluble at body temperature is self-lubricating to aid in its ready attachment in a few seconds.

15 These and such other objects of my invention as may hereinafter appear will be best understood from a description of an embodiment thereof, such as is shown by the accompanying drawing.

20 In the drawing, Fig. 1 is a sectional view of the female pelvis showing my improved combination pessary and suppository in place.

Fig. 2 is a perspective view of my improved combination pessary and suppository.

25 Fig. 3 is a central longitudinal sectional view thereof.

Fig. 4 is a cross sectional view thereof taken along the line 4-4 of Fig. 3.

In the drawing, wherein like characters of 30 reference indicate like parts throughout, 10 generally indicates an improved combination pessary and suppository constructed in accordance with my invention. In order that its functioning may be best understood I have shown in Fig. 1

35 a central sectional view through a normal pelvis of a female human being showing my improved combination pessary and suppository attached around the cervix and in this drawing I have indicated the usual pear shaped uterus 12, the

40 cervix or neck portion 14 of the womb which normally projects into the vagina 16, the os cervix 18 or opening from the womb or uterus into the vagina, the bladder 20, the urethra 22, the rectum 24, the anus 26 and the major and minor 45 labia 28 at the entrance to the vagina.

My improved pessary and suppository is preferably generally of thimble shape and includes a substantially semi-spherical head 30 adapted to overlie the os cervix 18 and side wall 32 preferably flaring outwardly as at 34 on the inner surface thereof towards the open lower end thereof to compactly selectively engage the inner surface of the side wall thereof on different size cervices to retain it thereon by suction and/or friction. The body 36 of my improved combination pessary and suppository 10 comprises a substance slowly soluble at body temperature and containing evenly dispersed therein a suitable medicament, said body being slowly soluble at body temperature to release said medicament over a relatively long period of time.

I preferably incorporate within said body portion 36 an imperforate frame or core to act even after the medicated soluble coverings thereof have been dissolved as a positive mechanical barrier to direct introduction of foreign material into the uterus and for this purpose I provide the core or frame 38 of paper, cloth, or other preferably fibrous material to not only strengthen 55 the pessary, but also completely to cut off the neck of the womb over a relatively long period of time.

The frame or core is preferably imperforate and preferably also somewhat resilient. When 75 the pessary is inserted therefore, the rim of the

pessary also becomes somewhat bendable to readily accommodate the pessary to different sized cervices and permit it to be resiliently retained thereon by suction. Said frame 38 also includes the semi-spherical head 40 adapted to 5 overlie the os cervix 18 and the side wall 42 flaring outwardly toward the open lower end 44 of said pessary for the aforesaid purpose of compactly engaging the side walls of different size cervices to be retained thereon by suction and/or friction. Around the core 38 is compressed or moulded a body 36 preferably comprising an inner and outer covering for the walls of said frame slowly soluble at body temperature. Said inner covering 46 and outer covering 48 preferably simultaneously formed having a suitable medicament, preferably uniformly incorporated therein and being slowly soluble at body temperature are adapted to release said medicament around the cervix, and adjacent portions of the 20 vagina over a relatively long period of time. These coverings 46 and 48 are designed to melt slightly above body temperature and only exude a small part of their structure at a time. These layers 46 and 48 may be made of glycerinated 25 gelatine (as stated in U. S. P. one-half glycerine and one-half gelatine), or a combination of paraffin substantially 75% and cocoa butter 25% (oil of theobroma). The melting point of these layers may be adjusted by varying the proportions of these ingredients and by the addition of a wax such as spermaceti. I prefer the second formula because of its lubricating value, consistency, non-irritating qualities and because it keeps better. Many other solid vegetable or animal oils might be used as for example, palm oil, nutmeg butter, shea butter, laurel, bone fat, butter fat, hog lard, beef and mutton tallow and the melting points thereof can be adjusted by the addition of a substance such as beeswax or 40 spermaceti. The fats thereof may be protected against rancidity by the addition of 10% benzoin.

To provide medicaments immediately effective on the insertion of the pessary, I preferably also 45 provide a medicated covering 50 for the outer surface of said layer 48 immediately soluble at body temperature when said pessary is attached, to immediately release a supply of said medicament to immediately tend to positively kill all 50 disease germs as they are introduced into the vagina. As shown I preferably build up this outer layer 50 to provide it with substantially parallel outer side walls 52 as against the taper of the inner side walls of the layer 46 to permit it 55 to contain a relatively large medicated dose on its uppermost portion where most needed to thoroughly dispense medicament around the adjacent portions of the vagina. I also provide a medicated globule or covering 54 for the inner surface 60 of the head 30 of said pessary also immediately soluble at body temperature when said pessary is attached to immediately release a supply of medicament immediately adjacent the os cervix. In the layers 50 and 54 I preferably employ cocoa 65 butter, adjusting its melting point at or just under the body temperature by the addition of spermaceti, or other wax. Cocoa butter has a rather sharp melting point remaining perfectly solid until this point is reached and then liquefy- 70 ing at once.

For the medicating of the layers 46 and 48 of body 36 and layers 50 and 54 of my improved pessary, it is apparent that a wide variety of medicaments may be used depending on the par- 75

ticular requirements of the patient. For general purposes I approve the addition of 4% boric acid, and 1% lactic acid to the base. Other formulæ might contain quinine bisulphate, quinine hydrochloride, trioxymethylene powder or other stronger, or more specific medicaments, such as described in the standard Formulary of Pharmaceutical Preparations or other suitable antiseptic or germicide.

- 5 10 In use, the pessary is inserted into the vagina and pushed backwards and upwards. In general it will guide itself over the firm cervix when it may be then pressed firmly into place. It should be left for several hours after intercourse, then 15 removed by hooking the finger under the edge and pulling it out. Both insertion and withdrawal are preferably done with the knees drawn up and spread apart and requiring if this attitude be assumed only a relatively few seconds.
- 20 20 It is apparent therefore that I have provided an improved type of combination pessary and suppository with the advantages carefully delineated above.

It is understood that my invention is not limited 25 to the specific embodiment shown and that various deviations may be made therefrom without departing from the spirit and scope of the appended claims.

What I claim is:

- 30 1. A consumable combination pessary and suppository having relatively thin walls and a substantially semi-spherical head adapted to overlie the os cervix and side walls flaring outwardly towards the open lower end thereof to compactly engage the side walls of different sized cervices and be additionally retained thereon by suction comprising a resilient imperforate frame or core constructed of fibrous or like material, medicated coverings for the inner and outer walls of said 35 frame slowly soluble at body temperature to release said medicament over a relatively long period of time, a medicated covering for the outer surface of said outer covering built up to provide substantially parallel outer side walls for said pessary to contain a relatively large medicated dose immediately soluble at body temperature when said pessary is attached to immediately release said supply of medicament and a medicated globule for the inner surface of the head 40 of said pessary also immediately soluble at body temperature when said pessary is attached to immediately release a supply of medicament immediately adjacent the os cervix.

- 45 2. A consumable generally thimble shaped combination pessary and suppository, comprising a body having a relatively thin substantially semi-spherical head adapted to overlie the os cervix and a relatively thin side wall having an inner surface flaring outwardly towards the open lower end thereof to compactly engage the side walls of different sized cervices and be additionally retained thereon by suction and comprising a resilient imperforate frame or core constructed of fibrous or like material, medicated coverings for the inner and outer walls of said frame slowly 50 soluble at body temperature to release said medicament over a relatively long period of time, a medicated covering for the outer surface of said outer covering built up to provide substantially parallel outer side walls for said pessary to contain a relatively large medicated dose immediately soluble at body temperature when said pessary is attached and a medicated covering for the inner surface of the head of said pessary also immediately 55

60 soluble at body temperature when said pessary is attached.

3. A consumable combination pessary and suppository comprising a body having a relatively thin substantially semi-spherical head adapted to overlie the os cervix and relatively thin side walls flaring outwardly towards the open lower end thereof to compactly engage the side walls of different sized cervices and be retained thereon by suction including a medicated surface for said pessary slowly soluble at body temperature to release said medicament over a period of several hours and then to release said pessary due to increase in diameter of the interior of the side wall thereof, and a medicated globule for the inner 15 surface of the head of said pessary immediately soluble at body temperature when said pessary is attached.

4. A consumable combination pessary and suppository comprising a medicated body slowly 20 soluble at body temperature to release said medicament over a relatively long period of time having a substantially semi-spherical head adapted to overlie the os cervix and a relatively thin side wall having an inner surface flaring 25 outwardly towards the open lower end thereof to compactly engage the side walls of different sized cervices and be retained thereby by suction and a medicated covering for the outer surface of said body built up to provide substantially parallel 30 outer side walls for said pessary to contain a relatively large medicated dose immediately soluble at body temperature when said pessary is attached.

5. A consumable combination pessary and suppository comprising a medicated body slowly 35 soluble at body temperature to release said medicament over a relatively long period of time having a substantially semi-spherical head adapted to overlie the os cervix and a relatively 40 thin side wall having an inner surface flaring outwardly towards the open lower end thereof to compactly engage the side walls of different sized cervices and be retained thereby by suction, a medicated covering for the outer surface of said 45 body built up to provide substantially parallel outer side walls for said pessary to contain a relatively large medicated dose immediately soluble at body temperature when said pessary is attached and a medicated covering for the inner 50 surface of the head of said pessary also immediately soluble at body temperature when said pessary is attached.

6. A consumable combination pessary and suppository comprising a medicated body slowly 55 soluble at body temperature to release said medicament over a relatively long period of time having a relatively thin substantially semi-spherical head adapted to overlie the os cervix and a relatively thin side wall having an inner 60 surface flaring outwardly towards the open lower end thereof to compactly engage the side walls of different sized cervices and be retained thereon by suction and a medicated covering for the outer surface of said body immediately soluble at body 65 temperature when said pessary is attached.

7. A consumable combination pessary and suppository comprising a relatively thin substantially semi-spherical head adapted to overlie the os cervix and a relatively thin side wall having 70 an inner surface flaring outwardly towards the open lower end thereof to compactly engage the side walls of different sized cervices and be retained thereon by suction including a medicated surface slowly soluble at body temperature to 75

release said medicament over a period of several hours and then to release said pessary due to increase in diameter of the interior of the side wall thereof.

- 5 8. A consumable combination pessary and suppository comprising a resilient imperforate frame or core constructed of fibrous or like material having a substantially semi-spherical head adapted to overlie the os cervix and side walls flaring outwardly towards the open lower end thereof and medicated coverings for the inner and outer walls of said frame to compactly engage the side walls of different sized cervices and be additionally retained thereon by suction only 10 slowly and completely soluble at body temperature to release said medicament over a relatively long period of time.

- 20 9. A consumable combination pessary and suppository comprising an imperforate frame or core having a substantially semi-spherical head adapted to overlie the os cervix and side walls flaring outwardly towards the open lower end thereof and medicated coverings for the inner and outer walls of said frame to compactly engage the side walls of different sized cervices and be retained thereon by suction only, slowly and completely soluble at body temperature to release said medicament over a relatively long period of time.

- 25 10. A consumable combination pessary and suppository comprising a resilient frame or core having a substantially semi-spherical head adapted to overlie the os cervix and side walls flaring outwardly towards the open lower end thereof and medicated coverings for the inner and outer walls of said frame to compactly engage the side walls of different sized cervices and be additionally retained thereon by suction only, slowly and completely soluble at body temperature to release said medicament over a relatively long period of time.

- 30 11. A consumable combination pessary and suppository comprising a frame or core having a relatively thin substantially semi-spherical head adapted to overlie the os cervix and relatively thin side walls flaring outwardly towards the open lower end thereof and relatively thin medicated covering for the inner and outer walls of said frame to compactly engage the side walls of different sized cervices and be additionally retained thereon by suction only, slowly and completely soluble at body temperature to release said medicament over a relatively long period of time.

- 35 12. A consumable combination pessary and suppository comprising a medicated body slowly soluble at body temperature to release said medicament over a relatively long period of time having a relatively thin substantially semi-spherical head adapted to overlie the os cervix and relatively thin side walls flaring outwardly towards the open lower end thereof to compactly engage the side walls of different sized cervices

40 and be additionally retained thereon by suction, a medicated covering for the outer surface of said body built up to provide substantially parallel outer side walls for said pessary to contain a relatively large medicated dose immediately soluble at body temperature when said pessary is attached to immediately release said supply of medicament and a medicated covering for the inner surface of the head of said pessary also immediately soluble at body temperature when said pessary is attached to immediately release a supply of medicament immediately adjacent the os cervix.

45 13. A consumable combination pessary and suppository comprising a resilient imperforate frame or core constructed of fibrous or like material having a substantially semi-spherical head adapted to overlie the os cervix and side walls flaring outwardly towards the open lower end thereof and a medicated covering for the inner and outer walls of said frame to compactly engage the side 20 walls of different sized cervices and be retained thereon by suction only, slowly and completely soluble at body temperature to release said medicament over a relatively long period of time.

50 14. A consumable combination pessary and suppository comprising a medicated body slowly soluble at body temperature to release said medicament over a relatively long period of time comprising a frame or core having a relatively thin substantially semi-spherical head adapted to 30 overlie the os cervix and relatively thin side walls flaring outwardly towards the open lower end thereof, a medicated covering for the inner and outer walls of said frame to compactly engage the side walls of different sized cervices and be 35 additionally retained thereon by suction and a medicated globule for the inner surface of the head of said pessary also immediately soluble at body temperature when said pessary is attached to immediately release a supply of medicament 40 immediately adjacent the os cervix.

55 15. A consumable generally thimble shaped combination pessary and suppository comprising a medicated body slowly soluble at body temperature to release said medicament over a relatively 45 long per'od of time comprising a frame or core having a relatively thin substantially semi-spherical head adapted to overlie the os cervix and relatively thin side walls flaring outwardly towards the open lower end thereof, a medicated 50 covering for the inner and outer walls of said frame to compactly engage the side walls of different sized cervices and be additionally retained thereon by suction and a medicated covering for the outer surface of said body built up to provide 55 substantially parallel outer side walls for said pessary to contain a relatively large medicated dose immediately soluble at body temperature when said pessary is attached to immediately release said supply of contraceptive medicament. 60

GEORGE A. CRUICKSHANK.
